(74) Attorney, Agent, or Firm — Bose Corporation

(57) **CLAIM**

The ornamental design for an earbud, substantially as shown and described.

DESCRIPTION

FIG. 1 is a perspective view of an earbud as seen from the left side and front, “left” being the observer’s point of view, and “front” being towards the observer, showing the new design; the opposite earbud is a mirror image; FIG. 2 is front view thereof;

FIG. 3 is a right side view thereof;

FIG. 4 is a back view thereof;

FIG. 5 is a left side view thereof;

FIG. 6 is a top end view thereof; and,

FIG. 7 is a bottom end view thereof.

The dotted line portions of the drawings represent environmental structure only and do not form part of the claimed design.
